UNITED STATES PATENT OFFICE.

GLEN G. WEINMAN, OF COLUMBUS, OHIO.

GAS-BURNING ATTACHMENT FOR FURNACES.

No. 899,275.

Specification of Letters Patent.

Patented Sept. 22, 1908.

Application filed March 7, 1908. Serial No. 419,678.

To all whom it may concern:

Be it known that I, GLEN G. WEINMAN, a citizen of the United States, residing at Columbus, in the county of Franklin and State of Ohio, have invented a certain new and useful Improvement in Gas-Burning Attachments for Furnaces, of which the following is a specification.

The principal object of this invention, among others, is to provide a gas burner adapted for ready attachment to the ordinary doorway of a furnace originally designed for the consumption of coal, so that no expensive alterations need be made to convert such furnace into one for the consumption of gas.

The invention is especially adapted to fill a want in those regions where natural gas in abundance has been discovered and by its comparative cheapness, cleanliness and convenience renders it necessary or profitable either to install a new furnace adapted to the consumption of gas, or to convert the old coal burning furnace into one adapted to such new fuel. To install a new furnace is highly expensive and to make the changes in an old one, as heretofore proposed, was costly and troublesome.

The invention is exemplified in the construction herein shown and described, the invention not being confined to the particular form of the parts shown.

In the accompanying drawings—Figure 1 is a vertical sectional view on the line $x-x$ Fig. 2 showing some parts in full; Fig. 2 is a front view with parts broken out to illustrate details.

In the views 3 designates a plate that is to be secured in a suitable manner over the opening where the usual door is provided. This plate is made with an opening 3^a that has secured in it, by rivets 4^a, a hollow thimble-like open frame 4 of rectangular form and having its inner front edges bent or turned inward in the form of a lip as seen at 4^b to stand across the spaces between the hinged edges of the deflecting plates (hereinafter described) and the outer end of the thimble and thereby insure the entrainment of air between the inner sides of said plates and prevent it from passing between the outer sides of said plates and the walls of the thimble. Hinged to several ears, as seen at 4^c, in the upper and lower cavities at the front of the frame 4 are two plates 5 and 6, respectively, each of which is capable, independently of

the other, of being swung up or down in that portion of the frame 4 which projects into the furnace. The vertical walls of the thimble close the spaces between the side edges of the deflector plates and confine or direct the fuel to pass between the inner edges of said plates. Pivoted to each of the plates on ears, as seen at 5^a and 6^a, is a curved rack arm, as seen at 7 and 8, respectively. These rack arms 7 and 8 extend to the exterior of the furnace through holes 4^d and 4^e both conveniently on the same side of the frame 4.

The teeth on each rack arm are on its lower edge, so that the arm can engage and rest by gravity on the edge at the lower end of the hole in the frame 4 through which it extends. The outer extremity of each of the rack arms is furnished with a suitable handle, as seen at 7^a and 8^a, respectively, and by means of which the arm can be adjusted, either inward or outward, and the plate raised or lowered to change its inclination. It will, therefore, be observed that by adjusting the arms 7 and 8 the inner free edges of the plates 5 and 6 can be moved nearer together or farther asunder. It will also be observed that by suitably elevating both plates from the position shown a flow of gas inward will be deflected upward, and conversely, by suitably lowering both plates, the flow of gas inward would be deflected downward.

9 designates the gas-supply nozzle. This is preferably of horizontally elongated form and located parallel to the opening between the plates 5 and 6, and somewhat removed from the plane of the face of the plate 4, so that a suitable quantity of air for admixture with the gas can be entrained with the gas. The fuel is ignited at or near the inner edges of the deflecting plates 5 and 6 and burns in the fire chamber with varying intensity, according to the quantity of fuel supplied and admixed air. The quantity of fuel supplied through the nozzle can be regulated by an ordinary valve as at 10.

With this invention a steady heat under the boiler can be maintained and this heat can be varied and directed with great nicety by adjusting the deflector plates 5 and 6. For example, the issuing flame can be directed upward directly against the boiler tubes, or it can be directed away from said tubes, and thus with the same supply of fuel vary the effect on the boiler.

My invention can be applied to many furnaces originally designed to use coal, it being

only necessary to remove the usual fire-chamber door and bring in the gas-supply equipment.

What I claim and desire to secure by Letters Patent is:

- 5 1. A gas burning attachment for furnaces comprising, in combination, a thimble-like frame 4, open at its front and rear ends, and provided at its front end with an outwardly standing flange whereby it may be attached to a furnace doorway and an inwardly standing lip, deflecting plates hinged, each at one of its edges, to the upper and lower edges respectively of the front end of said frame and
- 10 15 in rear of said inwardly standing lip, so that the latter shall obstruct the opening between the hinged edges of the deflecting plates and the frame, and arms 7 and 8 operatively engaging said deflecting plates respectively, said arms adapted to engage said frame to hold the plates in different positions to which
- 20

they may be adjusted, substantially as described.

2. A gas burning attachment for furnaces comprising, in combination, a thimble-like frame 4 open at its front and rear ends and provided with means whereby it may be attached to a furnace doorway, and with an inwardly turned lip 4^b at its front or mouth end, deflecting plates 5 and 6 hinged respectively to the upper and lower edges of the front end of said frame, and arms 7 and 8 operatively engaging the ends of said deflector plates respectively, said arms adapted to engage said frame to hold said deflector plates in different positions to which they may be respectively adjusted, substantially as described.

GLEN G. WEINMAN.
